UNITED STATES PATENT OFFICE.

MARC RESEK, OF EAST CLEVELAND, OHIO, ASSIGNOR TO PERFECTION STOVE COMPANY, OF CLEVELAND, OHIO, A CORPORATION OF OHIO.

BROODER.

Application filed May 21, 1924. Serial No. 714,761.

This invention relates to improvements in brooders of the so-called "colony" type.

Brooders of the type referred to comprise a comparatively shallow hood that is supported by legs a suitable distance above the floor and centrally beneath which is situated a heater.

The objects of the invention are to provide a brooder of the type aforesaid that is highly efficient in the matter of conservation and distribution of heat; and, conversely, is economical in the matter of fuel consumption; that is well ventilated and therefore free from obnoxious and injurious fumes or gases; that is simple of construction and comparatively cheap of production; and, especially in the larger sizes, is of a knock-down or sectional construction so as to facilitate packing, shipment and storage, and which, as a knock-down apparatus, is especially convenient of assembly and disassembly.

These and additional objects which will hereinafter appear and which relate more to structural details are attained in the embodiment of the invention illustrated in the accompanying drawings.

In the drawings, Fig. 1 is a sectional side elevation of a brooder constructed in accordance with my invention; Fig. 2 is a detail of one of the hood sections; Fig. 3 is a horizontal section through the edge portions of adjoining hood sections, showing the manner of attaching the sections together at the periphery of the hood and of securing the leg to the sections; Fig. 4 is a sectional detail on the line 4-4 of Fig. 3; and Fig. 5 shows fragments of the parts comprising a section of the hood, in perspective and in separated condition.

The hood, designated generally by the numeral 1, is preferably made up of a plurality of identical sections (three sections being employed in the present design) and each section comprises an inner plate 45 having side flanges 46 over which the relatively shallow side flanges 47 of the outer plate 48 are engaged. Tongues 49 which extend from the upper edges of the flanges 46 are arranged to be extended through slots 50 (Fig. 5) in the outer plate 48 and turned over therebeyond to bind the inner and outer plates together, the plates being properly spaced apart by the side flanges 46 of the

inner plate. Between the inner and outer plates is a partition plate 51 which has side flanges 52 that bear upon the inner plate 45 immediately inside its flanges 46, and tongues 53 extend from the flange 52 through slots 54 in the inner plate and they are turned over therebeyond so as to hold the partition 51 in place. As will appear from Fig. 1, the partition 51 stops short of the outer edges of the plates 45 and 48, but at its inner end is extended to the apex of the cone which it and the corresponding partitions of the other sections form when the hood is assembled. It may be explained at the same time that the inner edges of the plates 45 and 48 are curved and, with the inner edges of the corresponding plates of the other sections, surround central openings that are designated 55 and 56 in Fig. 1.

The outer edges of the inner and outer plates 45 and 48 are connected together and properly spaced apart by an arcuate peripheral wall 57 that is seamed or otherwise secured to the edges of said plates. The sections of the hood are properly aligned and secured together at their outer edges through dowels 58 (see Figs. 2 and 3) which extend from the corresponding outer corners of the various sections and interengage with the adjacent corners of the adjoining sections. Each dowel has one of its ends fastened to the inner side of the peripheral wall 57 of the section whereby it is carried, as by means of rivets 60, and passes through an opening in the flange 46 of the adjoining section so as to lie along the inner side of the peripheral wall 57 of said adjoining section. A leg 62, having a cross member 63 at its upper end, is secured to the outer side of the joint between adjacent hood sections by screws 64 which pass freely through holes in the cross piece 63 and in the walls 57 and are threaded into tapped holes in the dowel 58. By this means the legs are secured to the hood, and the outer ends of the hood sections are fastened together.

When the knock-down hood is assembled the corresponding plates of the various sections constitute cone-like shells.

Applied to the underside of the central portion of the conical shell comprised of the plates 45 is an inverted conical deflector 65 which has a downwardly diverging peripheral flange 66 that bears against the inner

edge portions of the plates 45. Similarly applied to the outer conical shell comprised of the plates 48 is a cap 67 which has a cylindrical part 68 and an edge flange 69 that bears upon the adjacent edge portions of the plates 48. The deflector 65 and the cap 67 are drawn together by a bolt 70, the bolt passing through an aperture formed in the apex of the conical shell comprised of 10 the partitions 51. Spacers 71 may be inserted between the cap and the partition plates 51 and between said partition plates and the deflector 65 so as to positively maintain the parts in properly spaced relation. 15 The deflector 65 is provided with a series of holes 72, and the cap 67 with holes 73. A flue 74 may be placed over the cap 67 and positioned by the cylindrical portion 68 thereof.

20 An oil burner 75 is supported centrally beneath the hood and is provided with a drum 76. The burner is communicatively connected to a fuel supply pipe 77 by means of an elbow fitting 78 which is secured to 25 the pipe by a clamp 79, the burner being fastened to the pipe at a point diametrically opposite the elbow fitting by a clip 80, all of which is in accordance with common practice. At its end adjacent the burner, the pipe is supported from the floor by 30 a stand 81, and at its opposite end is inclined upwardly and secured to a distributing receptacle 82 that is supported by legs 83 a proper distance above the floor. An oil reservoir 84 is inverted over the distributing receptacle 82 and supplies fluid to the burner. The burner incorporates the usual wick adjusting means 85, said means being in the 35 nature of a hand wheel on the outer end of the wick raising spindle, the hand wheel having operative connection, through a yoke 86, with a shaft 87 that is rotatably supported within a tube 88 that is carried by brackets 89 from the supply pipe 77. The 40 outer end of the shaft 87 extends beyond the edge of the hood and has fastened to it a hand wheel 90 by means of which the wick of the oil burner may be raised and lowered through the intervention of the means just described. Wick stop mechanism designated generally by the reference numeral 91 is preferably employed for preventing the wick of the burner from being turned too high. The form of wick stop employed is 45 the same as that described and claimed in the patent to Lee S. Chadwick, Serial No. 1,306,101, dated June 10, 1919. Briefly, the wick stop mechanism comprises a stop plate 92 that is rigidly secured to the outer end 50 of the tube 88 and wherewith is adapted to cooperate a finger 93 that is urged by a spring 94 in a direction to engage a part 55 carried by the finger, with serrations 95 in the hand wheel 90.

60 To enable the operator to observe the

height of the flame as he adjusts the wick by means of the hand wheel 90, I provide a peek hole in the hood by forming registering openings 98 in the inner and outer plates 45 and 48 and in the partition plate 51 of 70 one of the hood sections and said openings are covered by sheets of mica or the like 99 that are held in place by frames 100.

75 A cylindrical screen 101 may be disposed about the burner to protect the chicks from contact therewith.

80 The operation of the apparatus will be readily understood. The products of combustion, rising from the burner, escape from beneath the hood through the openings 72 in the deflector 65 to the space between the inner plates 45 and the partition plates 51, the products descending through said space and passing about the edges of said plates 51 to the space above said plates from 85 which they escape through the holes 73 in the cap 67.

90 A flue, such as 74, may be engaged over the cylindrical part 68 of the cap 67 for carrying off the products of combustion.

95 With brooders of the type described, the hood is sometimes suspended by a suitable chain or cable and may be counter-balanced if desired, so that the hood may be easily raised and lowered, it proving convenient 100 to raise the hood for the purposes of cleaning the floor beneath the hood or for cleaning and inspecting the burner. When a flue is employed under such conditions it may be comprised of telescopic sections which enables the flue to be lengthened or shortened as the hood is lowered and raised. These facilities are common in the art and are deemed unnecessary of illustration.

105 Having thus described my invention, what I claim is:—

110 1. In a brooder, the combination of a combustion device, and a hood disposed over said device and comprising inner and outer walls that are spaced apart, said inner and outer walls having, respectively, inlet and outlet openings, a partition intermediate said walls and separating the respective openings thereof, a deflector applied to the inner wall and extending across its opening, the deflector having a series of holes, and a cap 115 surmounting the outer wall over its opening, said cap also having a series of holes.

120 2. In a brooder, the combination of a combustion device, and a hood disposed over said device and comprising inner and outer walls that are spaced apart, said inner and outer walls having, respectively, inlet and outlet openings, a partition intermediate said walls and separating the respective openings thereof, a deflector applied to the inner wall and extending over its opening, the deflector having a series of holes, and a cap 125 surmounting the outer wall over its opening, said cap also having a series of holes, and

means extending through aligning apertures in the cap, the partition and deflector for binding the parts together.

3. In a brooder, the combination of a hood made up of separable sections, legs for supporting the hood a suitable distance above a floor, the legs overlapping the adjoining sections, means for securing the legs to the sections and serving with the legs to fasten the sections together, and a heater disposed beneath said hood.

4. In a brooder, the combination of a hood comprised of separable sections, dowels extending from the respective sections and engaged within openings of adjoining sections thereby to properly position the sections with respect each to the others, means cooperating with said dowels for securing the sections together and involving parts for supporting the hood a suitable distance above a floor, and a heater under the hood.

5. In a brooder, the combination of a hood comprised of inner and outer walls that are spaced apart and a partition plate intermediate said inner and outer walls, the inner and outer walls having openings adjacent their central portions and having their outer edge portions connected together, the partition having a part which separates the openings of the inner and outer walls and having its outer edge spaced inwardly from the corresponding edges of said walls, said hood being divided on substantially radial lines into sections, means detachably securing the sections together, means supporting the hood a suitable distance above a floor, and a combustion device disposed beneath the hood.

6. In a brooder, the combination of a conical hood comprised of sections which meet on substantially radial lines, each section comprising inner and outer walls that are spaced apart and a partition intermediate said walls, the plates of the inner and outer walls stopping short of the apex of the cone thereby to provide openings and having their outer edges connected together, the partition extending to substantially the apex of the cone thereby to separate the openings of the inner and outer walls while the outer edge of the partition is spaced inwardly from the corresponding edges of the inner and outer walls, means for properly positioning and securing together the outer edges of the sections, a baffle applied to the inner side of the hood and extending about an opening defined by the upper edges of the inner walls of the sections, a cap surrounding the hood in opposed relation to the baffle, and means connecting the central portions of the cap and baffle whereby the

cap and baffle clamp the inner edges of the sections together.

7. In a brooder, the combination of a conical hood that is made up of sections that meet on substantially radial lines, each section comprising an inner and an outer wall and a partition intermediate said walls, the inner and outer walls of the sections stopping short of the apex of the cone and the partitions of the sections stopping short of the base of the cone, the lateral edges of the inner wall of each section being flanged upwardly to meet the corresponding edge portions of the outer wall, said edge portions of the outer walls being flanged downwardly over the flanges of the inner wall, tongues projecting from the flanges of the inner wall through slots in the outer wall beyond which they are turned over to secure the walls together, the partition having side flanges resting upon the inner wall and having tongues projecting through slots in the inner wall and beyond which said tongues are turned over to secure the partition to the inner wall, and means for securing the sections together in proper relation each to the others.

8. In a brooder, the combination of a conical hood that is comprised of sections that meet on substantially radial lines, each section being formed of an inner and an outer wall and a partition intermediate said walls, the inner and outer walls terminating short of the apex of the cone to provide openings at the central portion of the hood while the partitions stop short of the base of the cone, the inner and outer walls of each section being properly spaced apart and connected together through the flanged lateral edges of one of said walls, the partition having flanges along its lateral edges through which it is spaced from and connected to one of the walls, and means supporting the hood a suitable distance from a floor.

9. In a brooder, the combination of a combustion device, a hood disposed over said device and comprising a plurality of sections, each section consisting of spaced-apart inner and outer walls having, respectively, inlet and outlet openings, relatively narrow side walls connecting the lateral edges of the former walls, a partition intermediate the inner and outer walls and separating the respective openings thereof and extending from one side wall to the other, and means for connecting the sections of the hood together and for properly positioning them with respect to one another.

In testimony whereof, I hereunto affix my signature.

MARC RESEK.
